UNITED STATES PATENT OFFICE.

MARGARET LE GRAND JOHNSTONE, OF GLENRIDGE, NEW JERSEY,
ASSIGNOR TO CHENEY BROTHERS, OF SOUTH MANCHESTER,
CONNECTICUT, A CORPORATION OF CONNECTICUT.

DESIGN FOR A TEXTILE FABRIC.

No. 38,118.

Specification for Design.

Patented July 3, 1906.

Application filed June 1, 1906. Serial No. 319,768. Term of patent 3½ years.

To all whom it may concern:

Be it known that I, MARGARET LE GRAND, JOHNSTONE, a citizen of the United States, residing at Glenridge, Essex county, State of New Jersey, have invented a new, original, and ornamental Design for Textile Fabrics, of which the following is a specification, reference being had to the accompanying drawing, forming a part thereof.

The figure is a plan view of the fabric, showing my new design.

I claim—

The ornamental design for a textile fabric, as shown.

MARGARET LE GRAND JOHNSTONE.
